US0D1047894S

(12) **United States Design Patent** (10) **Patent No.:** **US D1,047,894 S**
(45) **Date of Patent:** **** Oct. 22, 2024**

(54) **THERMAL BATTERY ENCLOSURE**

(71) Applicant: **Intellihot, Inc.**, Galesburg, IL (US)

(72) Inventors: **Sridhar Deivasigamani**, Mundelein, IL (US); **Sivaprasad Akasam**, Round Rock, TX (US)

(73) Assignee: **Intellihot, Inc.**, Galesburg, IL (US)

(*) Notice: Patent file contains an affidavit/declaration under 37 CFR 1.130(b).

(**) Term: **15 Years**

(21) Appl. No.: **29/892,083**

(22) Filed: **May 12, 2023**

(51) LOC (14) Cl. **13-02**

(52) U.S. Cl.

USPC **D13/103**

(57) **CLAIM**

The ornamental design for a thermal battery enclosure as shown and described.

DESCRIPTION

FIG. 1 is a top front perspective view of a thermal battery enclosure, showing our new design;

FIG. 2 is a bottom front perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

In FIGS. 1-4 and 8, the broken lines depict portions of the article that form no part of the claimed design.

1 Claim, 8 Drawing Sheets
